UNITED STATES PATENT OFFICE

SAMUEL THIES, OF CINCINNATI, OHIO, ASSIGNOR TO THE CINCINNATI ADVERTISING PRODUCTS COMPANY, OF CINCINNATI, OHIO, A CORPORATION OF OHIO

LUMINOUS GLOBE

Application filed April 11, 1928. Serial No. 269,094.

This invention relates to glass globes of the character generally employed around gasoline filling stations, and which globes are generally of a drum shape, having two exposed, outwardly convexed faces carrying advertising matter. These globes generally are of milk white, opaline and translucent character. Globes of the character under consideration, are shown in U. S. Patent 10 1,322,968 and in the application of Mattmann, Serial 232,692, filed November 11, 1927.

Because of the character of the finish of such milk white globes, the gloss or high light often renders the advertising matter 15 upon the globes indistinguishable. Especially is this true should the observer look at the globe at other than approximately a right angle to the display faces of such globes. It has been found undesirable to 20 place the advertising matter upon the outer face of such globes, because atmospheric action destroys the advertising matter after a short period of time, wherefore any diminution of the gloss or high lights incident 25 to portrayal of advertising matter upon the outer faces of the display panels, while somewhat solving the problem, is not commercially practical, because of the early deterioration of the advertising display by the 30 elements.

This invention concerns itself with the reduction of the gloss or the high lights on globes of the character under consideration. The invention is explained as applied to 35 globes that carry the advertising matter beneath the outer exposed surfaces of the glass panels of such globes. The glass panels are treated upon their outer surface in the manner about to be described.

Fig. 1 is an elevational view of a globe of the character referred to.

Fig. 2 is a sectional view on line 2—2 of Fig. 1.

The glass panels 15 are mounted upon the 45 globe 10, for example, as shown herein and in the indicated application to Mattmann. Each panel 15, before mounting thereof on the globe, is immersed in a bath of hydrofluoric acid, with the face 30 thereof disposed upwardly while in such bath. The face 30

is that face of the panel which is intended for exposure to the atmosphere, and the shape or contour thereof is immaterial to the invention.

Sand is sprinkled over the face 30 of the 55 panel while in the bath. The layer of sand or like substance serves to retard the action of the acid upon the face 30, with the result that said face is but slightly etched. The etching of face 30 is in fact so slight that the 60 transparency thereof is hardly affected by the action of the acid. However, the etching of face 30 is sufficient to remove the gloss, which, because of its tendency to glaringly reflect light from outside sources, is detrimental to the effectiveness of the display. Etching to the extent disclosed herein removes the gloss without destroying the 65 transparency of the slightly etched surface. Consequently, matter painted or otherwise 70 placed upon the inner surface 31 of the panel, will appear to be painted directly upon the outer surface 30. The strength of the bath and the length of time that the panels are left therein, are related factors 75 and must be taken into consideration for determining the attainment of the desired results. If the bath is rather strong, the glass panels should remain in the bath a shorter 80 period of time for attaining the same results 85 that would be accomplished by a weaker solution.

Generally it will be found sufficient to leave the panels in the bath ten minutes, the bath being approximately a solution of about 85% hydrofluoric acid and 80% water.

After the panels 15 are removed from the bath, they are washed to check further action of the acid, and they are then dried. The advertising matter 16 may then be applied 90 to the rear or inner face 31 of the panel, for example, as shown at 16 on panels 15 shown herein and in the said application of Mattmann. Translucent paint may then be applied to face 31 to provide a background for 95 the characters 16. If desired, the advertising matter may be placed directly upon the sides or panels 11 and 12 of the globe 10 as shown herein and in the indicated Mattmann application, and the treated panels 15 100

may be placed over the advertising matter, to protect same from the elements. The panels 15 when treated as disclosed herein, are sufficiently transparent to permit clear and distinct display or observation of the advertising matter through the treated faces of the glass panels during either the day or night seasons. It is to be understood that the globes are illuminated at night, by means 10 of an electric lamp 19, placed inside the globe 10. The treated faces 30 of the glass panels 15 apparently effect a refraction or subduing of light rays to such an extent that the glare or high lights are substantially 15 eliminated, and are reduced to such extent that they become inconsequential factors.

The reference numerals in the accompanying drawings correspond with the reference characters in the drawing of the application 20 of Mattmann, aforesaid. The panels 15 when treated on their outer inner faces, in the manner described herein, are given the appearance of ground surfaces.

Similar, but not as effective results, may be 25 attained by treating the inner surface 31 of the panels 15 in the manner described.

What is claimed is:

1. A day and night sign comprising a globe having side portions, an illuminator in 30 the globe for interior illumination thereof, a translucent display panel mounted on the side portions of the globe the panel having an outer face and an inner face, and advertising indicia on the inner face of the panel, the 35 outer face thereof being slightly but uniformly etched to an extent producing a smooth slightly misty-appearing surface for reduction of high light and glare resulting from extraneous light and a soft nondazzling effect when illuminated from the 40 interior.

2. A day and night sign comprising a globe having a translucent side and a recess adjacent thereto, an illuminator in the globe 45 for interior illumination thereof, a translucent display panel mounted in the recess and adjacent the side of the globe the panel having an outer face and an inner face, and advertising indicia between the globe side 50 and the inner face of the panel, the outer face of the panel being slightly but uniformly etched to an extent producing a smooth slightly misty-appearing surface for reduction of high light and glare resulting 55 from extraneous light and a soft nondazzling effect when illuminated from the interior.

In testimony whereof, I have hereunto 60 subscribed my name this 29th day of March, 1928.

SAMUEL THIES.
